UNITED STATES PATENT OFFICE.

FRED. M. CROUSE AND RICHARD E. LEWIS, OF RACINE, WISCONSIN.

CORK-PRESS.

SPECIFICATION forming part of Letters Patent No. 360,340, dated March 29, 1887.

Application filed December 27, 1886. Serial No. 222,637. (No model.)

To all whom it may concern:

Be it known that we, FRED. M. CROUSE and RICHARD E. LEWIS, of Racine, in the county of Racine, and in the State of Wisconsin, have 5 invented certain new and useful Improvements in Cork-Presses; and we do hereby declare that the following is a full, clear, and exact description thereof.

Our invention relates to cork-presses; and 10 it consists in certain peculiarities of construction and combination of parts, to be herein-after described with reference to the accompanying drawings and subsequently claimed.

In the drawings, Figure 1 represents a perspective view illustrating the application of our invention; Fig. 2, a side elevation of our invention, partly broken away; and Fig. 3, a vertical transverse section.

Referring by letter to the drawings, A represents the base of our cork-press, ordinarily 20 cast in one piece, with a plate, B, that has a flange, C, the inner periphery of the latter being beveled toward said plate and provided with a series of serrations. Pivottally connected to the flanged side of the plate B, so as 25 to be eccentric to the center thereof, is a circular shell, D, having a beveled and serrated outer periphery in opposition to the bevel and serrations of the flange C of said plate. Suitably secured to the bolt or pin E, that serves 30 to pivotally unite the plate B and shell D, is one end of a hand-lever, F.

The shell D is provided with a socket, G, to receive a pin, H, by which rigid connection 35 is established with the lever F, and the plate B has a segmental slot, I, that serves as a guide for said pin. The lever F is preferably provided with an offset, J, that projects more or less over the flange C of the plate B; but, if 40 desired, this offset may be omitted.

In order that our device may be secured 45 permanently to a suitable support, we prefer to provide the base A with suitable perforations, K, as shown by Fig. 1.

In the operation of our invention a cork is 50 inserted between the opposing beveled and serrated faces of the flange C and shell D, and the latter operated by the lever F, to impart a rolling motion to said cork and a gradually-increasing pressure thereon. The gradually-increasing pressure is obtained by having the shell D eccentrically pivoted to the plate B, the bevel on the opposing peripheries of said shell and the flange C corresponding with the 55 usual taper of the corks.

By having the parts B D eccentrically connected, as above described, we provide a varying space between the flange on the plate and the outer periphery of the shell, thereby accommodating our device to corks of different 60 diameters.

The peculiar advantage derived by our device is that any sized cork can be acted upon and reduced to the desired diameter without cracking, this result being obtained by the 65 gradually-increasing and rolling pressure.

Having thus fully described our invention, what we claim as new, and desire to secure by Letters Patent, is—

1. In a cork-press, the combination of a 70 plate having a base-piece and flange, a shell of less diameter than the plate and eccentrically pivoted thereto, and a lever for actuating the shell, substantially as and for the purpose set forth.

2. In a cork-press, the combination of a 75 plate having a base-piece and flange serrated upon its inner face, a shell of less diameter than the plate, but eccentrically pivoted thereto and provided with serrations in opposition 80 to those on the flange of said plate, and a lever for actuating the shell, substantially as and for the purpose set forth.

3. In a cork-press, the combination of a 85 plate having a base-piece and flange beveled upon its interior face, a shell of less diameter than the plate, but eccentrically pivoted thereto and beveled upon its outer periphery in opposition to the bevel on the flange of said plate, and a lever for actuating the shell, substantially 90 as and for the purpose set forth.

4. In a cork-press, the combination of a 95 base cast in one piece with a plate having a circular flange and segmental slot, a circular shell eccentrically pivoted to the plate in opposition to the flange, a lever having one end thereof connected to the shell-pivot, and a pin arranged to engage the segmental slot and unite the lever with said shell, substantially as and for the purpose set forth.

In testimony that we claim the foregoing we have hereunto set our hands, at Racine, in the county of Racine and State of Wisconsin, in the presence of two witnesses.

FRED. M. CROUSE.
RICHARD E. LEWIS.
